(57) **CLAIM**

The ornamental design for a portable cooker stove, as shown and described.

DESCRIPTION

FIG. 1 is a top perspective view of the portable cooker stove shown with an inserted wind baffle and its lid in an open position to show internal compartments of the cooker stove. FIG. 2 is a rearside perspective view of the portable cooker stove shown with an inserted wind baffle and its lid in an open position.

FIG. 3 is a rear plan view of the portable cooker stove shown with an inserted wind baffle and its lid in an open position. FIG. 4 is a top plan view of the portable cooker stove shown with an inserted wind baffle and its lid in an open position. FIG. 5 is a top plan view of the portable cooker stove shown with its lid in a shut position.

FIG. 6 is a front plan view of the portable cooker stove shown with its lid in a shut position.

FIG. 7 is an end plan view of the portable cooker stove shown with its lid in a shut position.

FIG. 8 is an end plan view of the portable cooker stove shown with its lid in an open position.

FIG. 9 is a top perspective view of the portable cooker stove shown with its lid in a shut position.

FIG. 10 is a front plan view of the removable wind baffle of the portable cooker stove; and,

FIG. 11 is a rear perspective view of the removable wind baffle of the portable cooker stove.

The broken lines depict environment and form no part of the claimed design.
